UNITED STATES PATENT OFFICE.

JOSEPH F. REYMAN, OF BALTIMORE, MARYLAND, ASSIGNOR TO SOLOMON HIMMEL,
OF BALTIMORE, MARYLAND.

DESIGN FOR STORE-SHELVING.

56,566.

Specification for Design.

Patented Nov. 9, 1920.

Application filed May 24, 1920. Serial No. 383,988. Term of patent 7 years.

To all whom it may concern:

Be it known that I, JOSEPH F. REYMAN, a citizen of the United States, residing at Baltimore, Maryland, have invented a new and original Design for Store-Shelving, of which the following is a specification, reference being had to the accompanying drawing, forming part thereof.

The figure is a perspective view illustrating the invention.

I claim:

The ornamental design for store shelving, as shown.

In testimony whereof I have hereunto set my hand.

JOSEPH F. REYMAN.
